(57) **CLAIM**

The ornamental design for a data storage device with surface ornamentation, substantially as shown and described.

DESCRIPTION

FIG. 1 is a perspective view of a data storage device with surface ornamentation according to a first embodiment of my design;

FIG. 2 is a front view thereof;

FIG. 3 is a perspective view of a data storage device with surface ornamentation according to a second embodiment of my design; and,

FIG. 4 is a top view thereof.

The broken lines that form a perimeter around the claimed design define the bounds of the claimed design and form no part thereof. The other broken lines show environment and are for illustrative purposes only and form no part of the claimed design.
